DESIGN FOR A FEATHER HOLDING HAT ORNAMENT OR SIMILAR ARTICLE

Stephen Marinchak, Brooklyn, N. Y.

Application December 28, 1938, Serial No. 82,027

Term of patent 3½ years

To all whom it may concern:

Be it known that I, Stephen Marinchak, a citizen of Czechoslovakia and resident of Brooklyn, in the county of Kings and State of New York, have invented a new, original, and ornamental Design for a Feather Holding Hat Ornament or Similar Article, of which the following is a specification, reference being had to the accompanying drawing, forming part hereof, and in which

Fig. 1 is a side view of a feather holding hat ornament or similar article showing my new design,

Fig. 2 is a top view thereof, and
Fig. 3 is an end view thereof.

I claim:

The ornamental design for a feather holding hat ornament or similar article, substantially as shown.

STEPHEN MARINCHAK.
